[57] CLAIM

The ornamental design for a base for a telephone headset, as shown and described.

DESCRIPTION

FIG. 1 is a right side front perspective view of a base for a telephone headset showing my new design;

FIG. 2 is a top plan view;

FIG. 3 is a front elevation view;

FIG. 4 is a right side elevation view;

FIG. 5 is a left side elevation view;

FIG. 6 is a rear elevation view; and,

FIG. 7 is a right side front perspective view thereof showing, in phantom, a telephone headset resting therein.

The antenna has been shown broken away in FIGS. 3-6 for convenience of illustration. The broken line showing of FIG. 7 is for illustrative purposes only and forms no part of the claimed design.
